UNITED STATES PATENT OFFICE

FRANK KUHN, OF DETROIT, MICHIGAN, ASSIGNOR TO AMERICAN ELECTRICAL HEATER COMPANY, OF DETROIT, MICHIGAN, A CORPORATION OF MICHIGAN

THERMOSTATIC CONTROL FOR ELECTRIC HEATERS

Application filed September 26, 1927, Serial No. 222,056. Renewed July 7, 1930.

The invention relates to thermostatic controls for electric heaters having more particular reference to electrically heated laundry irons.

5 It is the object of the invention to obtain a construction in which there is a quick response to variations in heat; also one which permits ready attachment or detachment of the thermostatic element and further one requiring but slight modification in the construction of the heater as designed to be without thermostatic control. The invention therefore consists in the construction as hereinafter set forth.

10 15 In the drawing I have shown my improved thermostat as applied to a laundry iron and in which

Figure 1 is a vertical central longitudinal section.

20 Figure 2 is a perspective view of the heating unit with the thermostatic switch attached thereto.

Figure 3 is a plan view thereof.

25 Figure 4 is a sectional elevation showing the indirect electrical connections to the terminals S'.

Figure 5 is a plan view thereof showing the bridge connection when the thermostatic switch is removed.

30 A is the heat distributing base of the laundry iron. B is the electrical heating unit above said base and C the pressure plate for clamping the unit to the base. D is the hood provided with the usual handle E and 35 F is a stud rising from the base having the threaded portions F', F'' for engaging nuts G, G' respectively clamping the plate C and hood D.

My improved thermostat is located in a recess H within the base A preferably located 40 centrally of said base and between the stud F and the rear end. This recess is adapted to receive a thermostatic switch which, as specifically shown comprises an inverted U-shaped frame member I and the contact bars J and K secured thereto one of which is the thermostatic element. The members I, J, K are clamped to each other with intervening insulation L preferably of mica and by means 50 of a screw stud M it also forms one of the

electrical terminals connected to the bar K. The other terminal is a stud N which is electrically connected to the bar J while contact buttons O and P normally electrically connect said bars J and K. One of the buttons 55 O is secured to a screw threaded stud Q which extends upward through aligned apertures in the element B, pressure plate C and hood D to a control member R outside said hood.

The specific construction of this thermostatic switch is not essential to my invention 60 as any suitable construction may be employed which is distinct from the heating unit B and which is located within the recess H.

The heating unit B is preferably of the 65 armoured type and is centrally cut away for the passage upward of the studs M, N and Q without contact therewith. The usual terminal contacts S, and S' are attached to the unit. These project through an insulator block T 70 and outward through apertures in the hood for engagement with the cord socket. One of the terminals S' is not, however, directly electrically connected with a resistor within the unit but is attached to the stud M so that the 75 current in passing through the resistor must first travel through the bar K, contact buttons O and P, bar J and stud N which latter is coupled by the connector U with a resistor. The other end of the resistor is directly 80 connected to the terminal S so that normally the current passes in series through the resistor and thermostatic switch. Thus whenever the temperature within the base A exceeds the limit at which the switch is set, the 85 warping of the thermostatic bar will separate the contact buttons O and P which will break the circuit and prevent further heat generation.

As has been stated, one of the objects of 90 the invention is to apply the thermostatic switch to a standard construction of iron such as designed to be without thermostatic control. Thus the only modification required in such an iron is the forming of the recess H 95 in the base and the indirect connection between the terminal S' and the resistor. This indirect connection includes the conductors U and V which are respectively attached to the studs N and M preferably by screws W 100

and W'. Thus the only attachment between the element and the thermostatic switch is through these screws and by disengaging the same the element may at any time be detached; also by attaching a bridge conductor X as shown in Figure 5 the conductors U and V are directly connected so that the iron may be used without the thermostat. This greatly facilitates manufacture as the same 10 construction of iron is used for the thermostatically controlled irons and the irons without thermostats which dispenses with the necessity of keeping a large number of distinct parts in stock.

15 The terminal S' is insulated from the supporting bracket therefor S^o as indicated at S^o which compels the current to pass by way of the conductors U and V.

What I claim as my invention is:

20 1. An electric laundry iron comprising a heat distributing base having a recess therein extending centrally and longitudinally thereof, a heating unit and a pressor plate therefor arranged above said base and clamped

25 thereto, said unit and pressor plate being apertured in registration with said recess, supporting brackets electrically connected to opposite ends of said heating unit, plug-engaging terminal contacts mechanically sup-

30 ported on said brackets, one being electrically connected to and the other being insulated from the respective brackets, a thermostatic switch located in said recess, terminals for said thermostatic switch projecting through

35 the registering apertures in said unit and pressor plate, electric connections between one of said thermostatic terminals and said insulated terminal contact and electric connections between the other thermostatic terminal

40 and the bracket supporting said insulated terminal.

2. An electric laundry iron comprising a heat distributing base having a recess therein extending centrally and longitudinally 45 thereof, a heating unit and a pressor plate therefor arranged above said base and clamped thereto, said unit and pressor plate being apertured in registration with said recess, supporting brackets electrically connected to

50 opposite ends of said heating unit, plug-engaging terminal contacts mechanically supported on said brackets, one being electrically connected to and the other being insulated from the respective brackets, a thermostatic

55 switch located in said recess, terminals for said thermostatic switch projecting through the registering apertures in said unit and pressor plate, electric connections between one of said thermostatic terminals and said

60 insulated terminal contact, electric connections between the other thermostatic terminal and the bracket supporting said insulated terminal, and a bridge conductor adapted to be secured to the aforesaid electric connections

65 to short circuit said thermostatic switch.

3. An electric laundry iron comprising a heat distributing base having a recess therein extending centrally and longitudinally thereof, a heating unit and a pressor plate therefor arranged above said base and clamped thereto, said unit and pressor plate being apertured in registration with said recess, supporting brackets electrically connected to opposite ends of said heating unit, plug-engaging terminal contacts mechanically supported on said brackets, one being electrically connected to and the other being insulated from the respective brackets, a thermostatic switch located in said recess, said switch having two studs projecting upwardly therefrom through the registering apertures in said heating unit and pressor plate, a metallic strip secured to said insulated terminal contact and adapted to be removably secured to one of said studs, a second metallic strip secured to the bracket 85 for said insulated terminal and adapted to be removably secured to the other stud and a bridge conductor adapted to be secured to both of said metallic strips.

In testimony whereof I affix my signature. 90
FRANK KUHN.
